STOKER FUEL DEFLECTOR

Charles J. Surdy, Tuckahoe, N. Y., assignor, by
mesne assignments, to The Standard Stoker
Company, Inc., New York, N. Y., a corporation
of Delaware

Application March 22, 1934, Serial No. 716,758

7 Claims. (Cl. 110—101)

My present invention relates generally to fuel deflectors as employed with mechanical stokers for firing locomotive furnaces and the like, and it appertains especially to an embodiment of the 5 fuel deflectors as disclosed in the United States Letters Patent No. 1,947,723, granted February 20, 1934, to Nathan M. Lower.

Accordingly, this invention contemplates the provision of fuel deflectors and means associated therewith for bodily moving the deflectors longitudinally and transversely of the stoker feed conduit. Where more than one deflector is employed I prefer to arrange the operating mechanism for independent operation of each deflector.

15 In carrying out my invention, it is a specific object to provide a pair of upstanding deflectors oppositely disposed one at each side of the discharge mouth of the stoker, each deflector having a forward vane portion extending in the direction of the flow of the fuel through the conduit, and having a rearward portion disposed outwardly and at an obtuse angle from the forward vane portion, each deflector being movable independently of the other obliquely with respect to the 20 vertical medial plane of the stoker conduit, whereby the deflectors are moved across the stoker discharge conduit to form an expandable and contractible mouth therefor, shiftable longitudinally and transversely of the conduit.

30 Another object of my invention contemplates the pivotal mounting of the forward vane portion of each deflector with its respective rearward portion and these pivotally mounted forward vane portions are adjustable independently of 35 each other so that each deflector, aside from being bodily movable transversely and longitudinally of the conduit, has a forward vane portion movable about an upstanding axis, thereby producing fuel deflecting means very flexible in 40 operation to meet the conditions of firing as the exigencies may require.

These and other objects, such as the operating means for each deflector, and the novel construction of the parts and their relations one with another will be apparent upon the reading of the following specification in connection with the accompanying drawings, in which,

Figure 1 is a fragmentary central vertical section through the rear portion of a locomotive with the stoker fuel conduit in which my invention is embodied shown in similar section;

Figure 2 is a plan section taken on the line 2—2 of Figure 1;

55 Figures 3, 4, and 5 are sectional views taken

on the line 3—3, line 4—4, and line 5—5, respectively, of Figure 2;

Figure 6 is a plan section similar to Figure 2 showing a modification;

Figure 7 is a plan section similar to Figures 2 5 and 6 showing another modification; and

Figure 8 is a sectional view taken on the line 8—8 of Figure 7.

Referring now to Figures 1 to 5, inclusive, the boiler is shown at 10, its firebox at 11, and the backhead at 12 having a firing opening 13 therethrough. Fuel is delivered to the firebox by suitable stoker mechanism, only so much being shown as is necessary to a complete understanding of the invention. The stoker mechanism includes a conduit 14 which leads forwardly from a source of fuel supply and is provided with a laterally flaring discharge mouth 15 in communication with the firing opening 13 for delivering fuel thereto. Flanges such as 16 20 are provided at the sides of the conduit 14 for attaching it to the backhead 12.

In its bottom, the flared discharge mouth 15 is recessed or cut away as at 17 to receive the chambered jet table 18 which forms a continuation of the bottom of the conduit 14 and is provided at its forward end with jet openings such as 19. These openings 19 discharge jets of pressure fluid across the distributor plate 20 for projecting the fuel thereover to all parts of the 30 firebox.

A screw 21 advances the fuel through the conduit 14 and although as illustrated this screw terminates adjacent the plane of the backhead 12, it is obvious that it may extend forwardly 35 into the firing opening 13 or it may terminate an appreciable distance rearward of the position shown, without departing from the spirit of my invention.

In stoking devices of the character described 40 and illustrated, it has been found in practice that the conveying screw has a tendency to discharge more fuel to one side of the stoker discharge mouth than to the other, depending on the direction of the flight windings and also upon 45 the direction of rotation. Thus, the fuel stream delivered in front of the jet openings 19 is of unequal volume so that more fuel is spread over one side of the firebox than the other side, causing troublesome fire conditions.

50 This invention provides means to overcome this uneven delivery and distribution of the fuel. In accomplishing this desirable result, I provide a pair of oppositely disposed deflectors 22, 23, one at each side of the stoker conduit and preferably 55

in the flared discharge mouth 15 thereof. The deflectors 22, 23 are provided with forward fuel deflecting vane portions 24, 25, and the planiform rearward portions 26, 27, respectively. The forward vane portions 24, 25 are disposed substantially in the direction of the flow of fuel through the conduit 14, while the rearward portions 26, 27 extend at an obtuse angle from the respective forward portions to points exterior of the conduit.

The respective side walls 28, 29 of the conduit 14 at the discharge mouth thereof are provided with slots or apertures 30 and 31, respectively, through which pass respective rearward portions 26, 27 of the fuel deflectors. The exteriorly disposed ends of the rearward portions 26, 27 are provided with lateral extensions 32, 33 having forks 34, 35 which engage the annular grooves 36, 37 of the threaded nut members 38, 39, respectively. Threaded stems 40, 41 are screwed into the side walls 28, 29 closely adjacent the rearward portions 26, 27, respectively, and parallel thereto; the respective nut members 38, 39 are threaded along their respective stems. For ease of assembly, the lateral extensions 32, 33 are secured to the respective rearward portions 26, 27 by screws such as 45, although, if found convenient, they may be formed integrally therewith.

By the construction described, a novel and effective fuel deflecting system is provided that will deflect the desired quantities of fuel to selected portions of the distributing plate 20, and consequently, to the selected or desired portions of the firebox. Thus, should it be necessary to deliver more coal to the left side of the firebox, the fireman turns the nut member 39 in a direction which will cause it to move outwardly from the side wall 29 of the conduit. This will retract the rearward portion 27 of the deflector 23, and cause the forward vane portion 25 thereof to be moved rearwardly and outwardly. If necessary, the nut member 38 may be turned so as to cause the deflector 22 to move forwardly and inwardly of the mouth portion 15. This changes the course of the fuel flow so that a greater quantity of fuel is delivered onto the left side of the plate 20, and consequently to that side of the firebox. It will be understood that the deflectors 22, 23 may be moved bodily in various relations to the discharge mouth of the conduit, forming an expansible and contractible mouth at various points transversely and rearward of the fuel discharge edge formed by the front face 42 of the chambered jet table 18. To explain the movement of each deflector in another way, it may be said that the free end of each fuel deflecting portion moves in a plane which is spaced from and parallel to the oblique plane of movement of the rearward portion of each deflector. In Figure 6 there is shown a modification of my invention wherein the rearward portions 26b, 27b of the respective deflectors 22b, 23b extend through side walls of the conduit at an angle to the vertical medial plane passed through the conduit which is not so acute as the corresponding angle shown in Figure 2. By this construction, the forward portions 24b, 25b of the deflectors 22b, 23b, respectively, will have a greater movement transversely of the mouth 15 than the movement longitudinally of the conduit. In the construction shown in Figure 2, the movement longitudinally of the conduit is greater than the movement transversely thereof. However, it will be recognized that the particular angle is a matter which is governed by the expected conditions of service.

In Figures 7 and 8 I have shown another modification of my invention wherein the forward portions 24a, 25a of deflectors 22a, 23a are pivoted to the rearward portions 26a, 27a respectively by means of upstanding pins 50. As clearly shown in Figure 8, the rearward portions 26a, 27a carry the pins 50 having threaded upper ends 51 which are engaged by thumb nuts 52. By the use of the pivotal mounting for the forward vane portions of the deflectors, in conjunction with the other adjustable feature shown, it is possible to swing each forward portion about a pin 50 and also to move it transversely and longitudinally of the discharge mouth. This construction gives a wider range of control.

In order to swing the forward vane portion of a deflector about its pin 50, the thumb nut is loosened to ease the pressure between the adjacent faces 53, 54 of the forward and rearward portions, respectively, permitting turning of the forward vane portion. After the forward vane portion is set at the desired angle, the thumb nut 52 is tightened, to prevent movement of the deflector by the fuel stream.

It will be noted from an inspection of Figures 2, 6, and 7, and especially the latter two, that when a deflector is moved inwardly with respect to the fuel conduit, a slight pocket is formed between the included side wall of the conduit and the rearward portion of the deflector. However, these pockets do not offer any resistance to the flow of fuel through the conduit as it will be clearly understood that the fuel which is lodged in them will merely remain dormant. Upon retraction of the deflector, the oncoming fuel will carry this dormant fuel toward the distributor.

Having described my invention, I claim the following as new and useful in the art to which the structures pertain.

I claim:

1. In combination, a firebox having a wall with an opening therein, a stoker feed conduit having its discharge end communicating with said firebox through said opening, means for advancing fuel through said conduit, a fuel distributor adjacent the discharge end of the conduit having a face provided with a plurality of jet openings for discharging a pressure fluid propelling blast and including a distributor plate extending forward from said face below said jet openings, a pair of upstanding fuel deflectors oppositely disposed one at each side of the discharge end of the conduit and positioned to act upon the fuel prior to the action thereon of the pressure fluid blast, each of said fuel deflectors including a rearward portion and a forward vane portion angularly related with respect to said rearward portion, said rearward portion being movable to move said forward portion to intersect the face of the fuel distributor at different points transversely arranged with respect to the firing opening and means for so moving said rearward portion.

2. In combination, a firebox having a wall with an opening therein, a stoker feed conduit having its discharge end communicating with said firebox through said opening, means for advancing fuel through said conduit, a fuel distributor adjacent the discharge end of the conduit having a face provided with a plurality of jet openings for discharging a pressure fluid propelling blast and including a distributor plate extending forward from said face below said jet openings, a pair of fuel deflectors oppositely disposed one at each side of the discharge mouth of the

conduit and positioned to act upon the fuel prior to the action thereon of the pressure fluid blast, each of said fuel deflectors including a rearward portion and a fuel deflecting forward portion 5 pivotally mounted on an upstanding axis with respect to said rearward portion, the rearward portion of each deflector being mounted to extend obliquely with respect to the vertical medial plane of the conduit, and means operating each deflector independently of the other for bodily moving the said deflectors and their axes longitudinally and transversely of the conduit.

3. In combination, a firebox having a wall with an opening therein, a stoker feed conduit 15 having a discharge mouth communicating with said firebox through said opening, means for advancing fuel through said conduit, a fuel distributor adjacent the discharge mouth of the conduit having a face provided with a plurality 20 of jet openings for discharging a pressure fluid fuel propelling blast and including a distributor plate extending forward from said face below said jet openings, a pair of upstanding fuel deflectors oppositely disposed one at each side of the discharge mouth of the conduit, each deflector including a forward fuel deflecting vane 25 portion which extends in the direction of the flow of fuel through said conduit, and a rearward portion extending angularly with respect to the forward vane portion toward the adjacent side of the conduit and being mounted to extend obliquely with respect to the vertical medial plane 30 of the conduit, said rearward portion being movable to move said forward portion to intersect the face of the fuel distributor at different points 35 transversely arranged with respect to the firing opening and means for so moving said rearward portion.

4. In combination, a firebox having a wall 40 with an opening therein, a stoker feed conduit having a discharge mouth communicating with said firebox through said opening, means for advancing fuel through said conduit, a fuel distributor adjacent the discharge mouth of the conduit having a face provided with a plurality 45 of jet openings for discharging a pressure fluid fuel propelling blast and including a distributor plate extending forward from said face below said jet openings, a pair of upstanding fuel deflectors oppositely disposed one at each side of the discharge mouth of the conduit, each deflector including a forward fuel deflecting vane 50 portion which extends in the direction of the flow of fuel through said conduit, and a rearward portion extending at an obtuse angle from the forward vane portion toward the adjacent side of the conduit and being mounted to extend obliquely with respect to the vertical medial plane 55 of the conduit, said rearward portion being movable to move said forward portion to intersect the face of the fuel distributor at different points 60 transversely arranged with respect to said firing opening and means for so moving said rearward portion.

5. In combination, a firebox having a wall 65 with an opening therein, a stoker feed conduit having a discharge mouth communicating with said firebox through said opening, means for advancing fuel through said conduit, a fuel distributor adjacent the discharge mouth of the conduit having a face provided with a plurality 70 of jet openings for discharging a pressure fluid fuel propelling blast and including a distributor plate extending forward from said face below

said jet openings, a pair of upstanding fuel deflectors oppositely disposed one at each side of the discharge mouth of the conduit, each deflector including a forward vane portion and a rearward portion, the forward portion of each deflector being pivotally mounted on an upstanding axis with its respective rearward portion and each rearward portion being mounted to extend obliquely with respect to the vertical medial plane of the conduit, each forward vane portion being 10 independently adjustable about its upstanding axis, and means for moving independently the rearward portion of each deflector obliquely with respect to the vertical medial plane of the conduit whereby the upstanding axis of each forward vane portion is shifted longitudinally and transversely of the conduit, said deflectors forming an expansible and contractible mouth for said conduit shiftable longitudinally and transversely thereof. 15

6. In combination, a firebox having a wall with an opening therein, a stoker feed conduit having a discharge mouth communicating with said firebox through said opening, means for advancing fuel through said conduit, a fuel distributor adjacent the discharge mouth of the conduit having a face provided with a plurality 20 of jet openings for discharging a pressure fluid fuel propelling blast and including a distributor plate extending forward from said face below said jet openings, a pair of upstanding fuel deflectors oppositely disposed one at each side of the discharge mouth of the conduit, each deflector including a forward vane portion and a rearward portion, the forward vane portion of each deflector being pivotally mounted with its respective rearward portion on an upstanding axis disposed rearward of said face and each rearward portion being mounted to extend obliquely with respect to the medial vertical plane 25 of the conduit, each forward vane portion being independently adjustable about its respective upstanding axis, and means for moving independently the rearward portion of each deflector obliquely with respect to the vertical medial plane 30 of the conduit whereby the upstanding axis of each forward vane portion is shifted longitudinally and transversely of the conduit, said deflectors forming an expansible and contractible mouth for said conduit shiftable longitudinally 35 and transversely thereof. 40

7. In combination, a firebox having a wall with an opening therein, a stoker feed conduit having its discharge end communicating with said firebox through said opening, means for advancing fuel through said conduit, a fuel distributor adjacent the discharge end of the conduit having a face provided with a plurality of jet openings 45 for discharging a pressure fluid propelling blast and including a distributor plate extending forward from said face below said jet openings, a pair of upstanding fuel deflectors oppositely disposed one at each side of the discharge end of the conduit and positioned to act upon the fuel prior to the action thereon of the pressure fluid 50 blast, each of said fuel deflectors including a rearward portion and a forward vane portion angularly related with respect to said rearward portion, said rearward portion being movable to move said forward portion to any one of a number 55 of planes intersecting the face of the fuel distributor at different points transversely arranged with respect to the firing opening and means for so moving said rearward portion. 60
